UNITED STATES PATENT OFFICE.

WILLIAM M. UNDERHILL, OF OCONTO, WISCONSIN.

IMPROVEMENT IN LAMP-PENDANTS.

Specification forming part of Letters Patent No. **170,607**, dated November 30, 1875; application filed July 10, 1875.

To all whom it may concern:

Be it known that I, WILLIAM M. UNDERHILL, of Oconto, Oconto county, Wisconsin, have invented a new and useful Improvement in Lamp-Pendants, of which the following is a specification:

Figure 1 represents my improved lamp-pendant, showing its position when the lamp is elevated. Fig. 2 represents the same, showing its position when the lamp is lowered. Fig. 3 represents a modified form of the same.

Similar letters of reference indicate corresponding parts.

My invention has for its object to furnish an improved pendant, which shall be so constructed as to allow the lamps to be conveniently lowered for cleaning and lighting them, or for a drop-light, which may be used in rooms with either high or low ceilings, and which shall be simple in construction and inexpensive in manufacture.

The invention consists in the rod provided with an eye, a band or loop, a hook, and a balancing-weight, or its equivalent, in combination with the stem by which it is suspended, and with the pendant of a lamp, as herein-after fully described.

A represents the stem, hook, or staple by which the pendant is suspended from the ceiling. B is the rod, in which, near one end, is formed an eye, b^1 , to receive the eye of the stem A. In the rod B, directly under the eye

b^1 , is formed a bend or loop, b^2 , to receive the eye c' of the pendant C of the lamp. In the end of the rod B is formed a hook, b^3 , to receive the eye c' of the pendant C when raised from the bend b^2 and slid along the rod B to lower the lamps. To the other end or short arm of the rod B is attached a weight of sufficient size to balance the long arm of the rod B when the said rod hangs free.

In cases where the ceiling is not so low the weight D may be replaced by an arm similar to the long arm of the rod B, and with a similar hook upon its end to give the device a symmetrical appearance, the said arm having no other use than as a counter-balance.

By this construction, by slipping the eye c' of the pendant C from the bend b^2 to the hook b^3 the lamps will be lowered the whole length of the arm B.

Having thus described my invention, I claim as new and desire to secure by Letters Patent—

The rod B, provided with an eye, b^1 , a bend or loop, b^2 , a hook, b^3 , and a balancing-weight, D, or its equivalent, in combination with the stem A, by which it is suspended, and with the pendant C of a lamp, substantially as herein shown and described.

WM. M. UNDERHILL.
